AND MANTEL

Reginald E. Beauchamp, Oaklyn, N. J., and Henry Louis Otto, Philadelphia, Pa., assignors to Artcrafter's Guild, Philadelphia, Pa., a co-partnership

Application May 10, 1933. Serial No. 48,070

Term of patent 7 years

To all whom it may concern:

Be it known that we, REGINALD E. BEAUCHAMP and HENRY LOUIS OTTO, citizens of the United States, the former residing in Oaklyn, in the county of Camden and State of New Jersey, and the latter residing in Philadelphia, in the county of Philadelphia and State of Pennsylvania, have invented a new, original, and ornamental Design for a Combined Bar Cabinet and Mantel, of which the following is a specification, reference being had to the accompanying drawing, forming part thereof.

Figure 1 is a perspective view of an open combined bar cabinet and mantel showing our new design.

bined bar cabinet and mantel closed up.

We claim,

The ornamental design for a combined bar cabinet and mantel as shown.

REGINALD E. BEAUCHAMP.
HENRY LOUIS OTTO.
